TUBULAR FABRIC SPREADER

Filed March 20, 1947

INVENTOR.

Thomas P. O'Malley

UNITED STATES PATENT OFFICE

2,507,599

TUBULAR FABRIC SPREADER

George A. Johnson, New York, N. Y., assignor to
 American Viscose Corporation, Wilmington,
 Del., a corporation of Delaware

Application March 20, 1947, Serial No. 736,015

11 Claims. (Cl. 26—55)

1

This invention relates to a device adapted to spread out a tubular fabric and is particularly concerned with that type of device which is adapted to float in a fixed position within the traveling tubular fabric, and is provided with rotary members spaced along its edges, with or without belts carried thereon, to engage the traveling fabric and thereby reduce the friction of such fabric along the edges of the spreader device.

It is the primary object of the present invention to provide improved driving means for driving at least some of the rotary members carried by the floating device.

Another object of the present invention is to provide a form of driving means which is adapted to independently control the speeds of the fabric-engaging members at the several edges of the device in order to straighten out the fabric whenever it becomes disposed in a crooked fashion upon the device because of any irregularity causing the fabric to feed faster along one side than the other or to slip relative to the driving means on one side more than on the other.

It is a further object of the invention to provide driving means carried by the device within the fabric which is magnetically coupled with external driving means in order to reduce or eliminate the friction against the fabric resulting from driving the spreader either by the travel of the fabric or by frictional engagement of external driving members against the fabric, such as driving rolls, pulleys, belts or the like.

Other objects and advantages will be apparent from the drawing and the description thereof hereinafter.

In the drawing, which is illustrative of the invention:

Figure 1 is a front elevation of the tubular fabric spreader, with the front panel of the fabric cut away and with the external driving means partially removed from the left side to expose the details of the spreader structure,

Figure 2 is a section taken on line II—II of Figure 1,

Figure 3 is a face view of a modified form of permanent magnet,

Figure 4 is a further modification of a permanent magnet rotor,

Figure 5 is still another modification of a permanent magnet rotor,

Figure 6 is a section of a belt line VI—VI of Figure 1, and

Figure 7 is a section taken on line VII—VII of Figure 1.

2

With reference particularly to Figures 1 and 2, the floating fabric spreader comprises a symmetrical framework having two generally parallel panels 3, both of which may have contours 5 similar to the contour of the front panel shown in Figure 1. Each panel comprises substantially identically shaped members joined at 4 and 5 by means of cap or machine screws 6 extending into a tie-rod or block 4a which has such a thickness 10 as to properly space the two panels apart so that they can receive therebetween a plurality of rotary members 7 adjacent the periphery of the panels. These rotary members 7 are rotatably mounted such as by means of pins 8 which extend into the spaced panels. The opposite panels 3 may be additionally secured together in properly spaced relation to form a rigid framework by additional spacer elements 4b in the form of internally threaded sleeves adapted to receive machine screws 6a (see Figure 7). The spreader may readily be adjusted to fabrics of different widths by replacing the tie-rods or blocks 4a secured at joints 4 and 5 by screws 6 with longer or shorter blocks.

25 As shown, the tubular fabric F passes upwardly around the floating spreader device and in order to spread the fabric gradually the lower ends of the panels are shaped into a gradually rounded nose. At a position above the center of gravity 30 of the assembled floating framework, the panels are indented as at 9 to provide a recess to receive external supporting rolls 10. One of the rotary elements 7 is positioned adjacent each side of the indented portions 9 so as to cooperate 35 with the external supporting rotors 10. The tail end of the panel comprises two outwardly extending legs 11 which serve to stretch the fabric to the full width as the fabric departs from the device. The outermost edges of the panels are 40 bent inwardly as shown in Figures 2 and 7 in order to avoid the engagement of the fabric with any sharp corners at such edges. The two panels are preferably formed in such a manner that along the outer edges of their legs 11 the spaced 45 panels come into substantial contact.

The supporting rotors 10 may either be idle or driven and if driven, they are preferably driven at a speed which is the same as the linear speed of the tubular fabric, so that there is no need 50 for any relative slipping of the rotors 10 against the fabric. Belt 12 may be passed around two or more of the rotary elements 7 carried by the device and when used, it serves to carry the fabric along that portion of the edge adjacent which 55 it extends. As specifically shown, two such belts

are provided, one for the rotatable elements 7 on one side and the other for the rotatable elements on the other side. Any belt which is capable of being tensioned may be employed but it is preferred to have a belt formed, as illustrated in Figure 6, of a coil spring 39 surrounded by or embedded in a sheath or cylindrical body 40 of rubber or equivalent material such as a synthetic or substitute rubber and, in any event, the outer surface of such belt should be rounded.

Regardless of whether or not the rotors 10 are idlers or driven, there is preferably provided within the floating device means for driving the rotatable elements 7. As shown specifically, this driving means comprises a permanent magnet rotor 13 having two poles as indicated at the left of Figure 1. The rotor 13 is preferably in the form of a solid disc, any space between the poles being filled with a hard non-magnetic material 14, such as a synthetic resin of the type of phenol-aldehyde, urea-aldehyde, or the like. In order to hold each rotor 13 in place, a set of three pulleys 15 are fixedly secured in a yoke 16 and the intermediate of such pulleys 15 has its axis offset from the plane of the axes of the outer two pulleys. The pivot 17 upon which the intermediate pulley 15 is mounted extends endwise from both plates of the yoke into slots 18 provided in the spaced panels 3 inwards of the location desired of the rotor 13. The belt 12 passes around the two or more (all as shown) rotatable elements 7 desired to be driven and also around the outer two pulleys 15 and is tensioned so that the several pulleys 15 with their yoke 16 are urged toward the rotor 13, slots 18 being disposed generally radially with respect to the rotor 13 in order to allow of such motion of the yoke and pulleys 15. A preferred manner of maintaining the plane of rotation of rotor 13 consists in providing the periphery with a frictional facing ring 19. Advantageously, this facing material rests within a groove 20 in the circumference of the rotor 13 and is provided with an annular bead 21 adapted to fit within the grooves of the pulleys or sheaves 7. This assures that the rotor is maintained in proper engagement with the rotary elements 7.

Means is provided for externally driving the magnetic rotors 13. This means consists in providing a rotating field alongside at least one face of the floating structure adjacent the position occupied by each rotor 13. As shown more particularly in Figure 2 and at the right of Figure 1, there are provided shafts 22 and 22a whose axes are in alignment with axis of rotor 13. A motor 23 drives shaft 22 and the rotation of shaft 22 is transmitted to shaft 22a by means of an offset shaft 24 supported in bearings 25, a belt or sprocket chain 26 connecting shaft 24 with shaft 22 and a similar belt or sprocket chain 27 connecting shaft 24 and 22a. Each shaft 22 and 22a carries a spider 28 having at its outer periphery four magnetic cores 29 each carrying an electromagnetic coil 30. Each shaft likewise carries two slip rings 31 and 32 which serve as terminals to which the leads 33 and 34 of each coil are connected. These leads 33 and 34 are connected to provide two north poles adjacent one another and two south poles adjacent one another, the several poles being spaced in a manner to adapt them best to the particular construction of the magnetic rotor 13 with which it is to co-operate. Brushes 35 and 36 are provided to connect the slip rings 32 and 31 respectively to opposite sides of a direct current line 37. It

is to be understood that a permanent magnet may be substituted for the spider 28 with its four electromagnetic poles and this may be fully adequate where a large torque is unnecessary to drive the rotative members 7.

Each of the rotors 13 co-operates with a separate and independent external driving means and the speed with which the external magnetic field is rotated may be controlled independently of the other driving field. This independent control may be obtained by disposing an infinitely variable speed transmission between the motor 23 and shaft 24 or by an electrical controlling means such as by the rheostat 38 connected in series with a series-wound A. C. motor. By thus providing independent control of the speed of rotation of the rotors, it is possible for an operator to straighten out a fabric at any time during operation that it becomes too taut on one side of the floating device and too loose on the other. This may be effected merely by momentary increase of speed on one side or reduction of speed on the other side.

Figure 3 shows a modified form of magnetic rotor 13a in the form of a ring of highly magnetic material permanently magnetized to provide alternating north and south poles. The dotted lines are lines of magnetic flux. Figure 4 shows a modification of the permanent rotor in which the disc 13b of strongly magnetizable material is magnetized to provide north and south poles alternating about its periphery.

Figure 5 shows a further modification of a magnetic rotor in which spaced discs 13c of non-magnetizable material have secured therebetween two separate bars 13d of highly magnetizable material. The bars are magnetized to provide alternating north and south poles about the periphery.

In all of the embodiments shown it is to be understood that the magnetic rotor may consist of permanently magnetized systems having one or more north poles and one or more south poles, the several north poles either alternating with the south poles or being grouped together as desired.

In operation, it will be apparent that the two rotors 13 in the two sides of the floating spreader will normally be driven at constant speed and at the same speed. By driving all of the rotatable elements 7 which engage the tubular fabric through the belts 12 thereabout at the same speed as the speed of withdrawal from the device, the friction between such elements and the fabric is reduced to a minimum and the floating device as a whole exerts a minimum of friction against the inside wall of the fabric. It is thus possible to substantially eliminate any drag caused by the rotors 10 upon the fabric. However, it is within the scope of applicant's invention to rely upon the driving of rotatable elements 7 entirely, in which case rotors 10 would be idlers. The supporting rotors 10 normally are in the form of grooved pulleys so that the groove is adapted to receive the fabric edge contour as determined by the belts 12.

It is an important feature of the present invention that the rotatable elements 7 along one side of the floating spreader are independent of the corresponding elements along the other side or sides insofar as driving means is concerned, whether such driving means be derived externally of the fabric by frictional engagement of the driving means therewith as by means of rotary members 10 or other electromagnetic cou-

pling through rotors 13. This adapts the floating spreader to driving systems which independently control the rate of travel of the fabric along the several edges of the spreader so that the fabric may be straightened out at will by the operator.

It is to be understood that changes and variations may be made without departing from the spirit of the invention as defined by the claims hereinafter.

I claim:

1. A spreader adapted to float within a traveling tubular fabric comprising a framework, a group of rotatable elements spaced along each edge of the frame, and, operatively associated with each group of the elements, means comprising a rotor disposed with its periphery adjacent that of one of the elements and a belt engaged therebetween for driving the elements along one side independently of the other rotatable elements.

2. A tubular fabric spreader in accordance with claim 1 having means for independently controlling the speed of rotation of the rotatable elements along the several edges of the spreader.

3. A tubular fabric spreader in accordance with claim 2 having a plurality of independent belts, each belt passing around a plurality of the rotatable elements along one edge only of the spreader.

4. A tubular fabric spreader in accordance with claim 1 having a plurality of belts, each belt passing around the rotatable elements on one side of the spreader.

5. A tubular fabric spreader in accordance with claim 1 having a plurality of permanent magnet rotors rotatably mounted thereon, each of such magnetic rotors being in driving engagement with at least one of the rotatable elements.

6. A tubular fabric spreader in accordance with claim 5, having external means for rotating a separate magnetic field in inductive relationship with each of the permanent magnets.

7. A tubular fabric spreader in accordance with claim 6 having means for independently controlling the speed of rotation of the rotating fields.

8. A spreader adapted to float within a traveling tubular fabric comprising a framework, rotatable elements spaced along each edge of the frame, means for driving the elements, and a permanent magnet rotor rotatably mounted on the spreader in driving engagement with at least one of the rotatable elements.

9. A spreader adapted to float within a travel-

ing tubular fabric comprising a framework, rotatable elements spaced along each edge of the frame, means for driving the elements along one side independently of the other rotatable elements, a plurality of permanent magnet rotors mounted on the spreader, each of such magnetic rotors being in driving engagement with at least one of the rotatable elements.

10. A spreader adapted to float within a traveling tubular fabric comprising two spaced panels having generally the same configuration, each panel comprising two approximately identical members joined together to provide a symmetrical structure in which one juncture is formed in the leading end of the device and another juncture is formed between inwardly extending transverse portions of the panel members near the trailing end of the device, each panel member being provided with inwardly extending portions intermediate of the nose of the device and the transverse portions of the panel forming the rear juncture, separate and independent belt-guiding means on each side of the spreader slidably mounted upon each of said inwardly extending panels, a plurality of rotatable elements disposed along each side of the spreader and mounted between the panels, a plurality of separate belts, each belt passing about said belt-guiding means and rotatable elements on a separate side of the device, a plurality of rotatable permanent magnets, one such magnet being associated with each side of the spreader and being in driving engagement with a plurality of rotatable elements along its side, a plurality of magnetic fields disposed outside said spreader, one such field being adjacent each permanent magnet, and means for rotating the fields.

11. A tubular fabric spreader in accordance with claim 10 having means for controlling the speed of the magnetic field associated with each permanent magnet independently of those associated with the other permanent magnets.
